Primary Examiner — Messina L Smith*Assistant Examiner* — Kwabena A. Ankobiah(74) *Attorney, Agent, or Firm* — Philip Oweimrin(57) **CLAIM**

The ornamental design for a LCD writing tablet, as shown and described.

DESCRIPTION

FIG. 1 is a front perspective view of a LCD writing tablet, showing my new design;
FIG. 2 is a rear perspective view thereof;
FIG. 3 is a front view thereof;
FIG. 4 is a rear view thereof;
FIG. 5 is a left side view thereof;
FIG. 6 is a right side view thereof;
FIG. 7 is a top view thereof;
FIG. 8 is a bottom view thereof;
FIG. 9 is an enlarged detail view of area 9 in FIG. 1; and,
FIG. 10 is an enlarged detail view of area 10 in FIG. 2.
The broken lines in the drawings illustrate portions of the LCD writing tablet that form no part of the claimed design. The dash-dot-dash broken lines encircling portions of the LCD writing tablet in FIGS. 1 and 2 and illustrated in an enlarged view in FIGS. 9 and 10 form no part of the claimed design.

1 Claim, 10 Drawing Sheets(56)
